UNITED STATES PATENT OFFICE.

FRANK L. ALBEN, OF WILKINSBURG, PENNSYLVANIA, ASSIGNOR TO WESTINGHOUSE ELECTRIC & MANUFACTURING COMPANY, A CORPORATION OF PENNSYLVANIA.

TRUCK SWING LINK.

Application filed November 7, 1922. Serial No. 599,521.

To all whom it may concern:

Be it known that I, FRANK L. ALBEN, a citizen of the United States, and a resident of Wilkinsburg, in the county of Allegheny and State of Pennsylvania, have invented a new and useful Improvement in Truck Swing Links, of which the following is a specification.

My invention relates to swing supporting structures, more especially to swing-bolster mountings of the type which permit of relative movement of the bolster and its support, such as are employed for effecting transfer of weight of vehicle bodies relative to their supporting wheels.

It is among the objects of this invention to provide a mechanism of the above-designated type which shall be of strong, durable, efficient and economical construction.

It is a further object of this invention to provide a swing-bolster mounting which is especially adapted to railway vehicles to provide proper steering action of the leading or trailing truck with the main vehicle body supports.

Various types of swing-link mountings have been proposed which embody a plurality of link suspensions by which a bolster plate is supported and which provide lateral movement of the bolster relative to the main truck frame to effect guiding action of the wheels on the rails.

My present invention is directed to a novel type of swing-link or swing-bolster construction which is adapted to provide positive relative movement of the body mounted thereon by means of a stable hinge joint which may be instantly changed to an idle swinging support. This is of particular advantage in railway vehicles where it is desired to provide positive steering action of the idle truck for varying curvatures of the rail when such truck is leading and free idle movement between the rails when it trails.

In the accompanying drawing constituting a part hereof and in which like reference characters designate like parts,

Figure 1 is a front elevational view of a pair of swing links embodying the principles of my invention;

Fig. 2 is a side elevational view of a single member;

Fig. 3 is a plan view; and

Fig. 4 is a cross-sectional view, partially in elevation, of a slightly modified form of link.

The structure comprises a pair of links 1, commonly designated heart links, the upper ends of which are connected by a plurality of bolts 2, having rollers 3 mounted thereon. A swing bolster 4, which is adapted to support a load, such as the center pin of a two-wheel truck member, is secured to the lower ends of the links 1 by a pivotal connection 5. The links 1 are supported on a main frame portion 6 at the center-bearing roller 3 which fits into a semi-cylindrical seat in a bearing member 7 that projects upwardly from the frame 6.

The links 1 are further adapted to be supported at the outer rollers 3 by a movable supporting block 8 which is adapted to move vertically in a guide 10, provided in the supporting frame 6. The movable block 8 is connected, by a plurality of links 11 and 12 which constitute a toggle joint, to a projecting bracket 13 extending from the main frame. The toggle links 11 and 12 are pivoted, respectively, to the movable supporting block 8 and the bracket 13 to effect relative movement between the block and the supporting frame. The toggles are connected together, by means of a suitable tie or connecting rod 15, to effect synchronous movement of the blocks 8 in their respective guides. A stop 17 is provided on one side of one of the toggle joints to limit its movement in one direction so that, when the toggle is in engagement therewith, it is comparatively stable.

The operation of the mechanism thus far described is briefly as follows. If it is desired to provide a free swinging suspension of the bolster plate 4, the connecting rod 15 is moved laterally to the right, which breaks the toggle joint and removes the support 8 from the outer rollers of the links 1, thus permitting the center roller 3 to engage its bearing member 7. The link is then free to swing on the bearing 7 and provides free swinging movement of the bolster plate 4. When the connecting rod 15 is placed in the position illustrated in Fig. 1, with one of the toggle members resting against the stop 17, the movable support or bearing block 8 is actuated to engage the outer rollers 3 of the link and raise the central roller 3 out of engagement with

its supporting bearing 7. In this position, the links are permitted to hinge about the outer rollers, such as an outer roller on one link and an inner roller on the coacting link, depending upon the direction of lateral thrust which is transmitted through the hinged bolster plate 4.

When the links are supported on the central roller 3, the supporting block 8 is disengaged from the outer rollers and drops downward in the guide 10 until the loop portion 19, which constitutes a stop, rests on the central roller 3.

The modified form of link and co-operating support shown in Fig. 4, is similar to that described above, with the exception that the movable blocks 8 are not disposed in guide-ways and, therefore, they do not require the relatively large face width that the blocks illustrated in Fig. 1 do. The blocks 8 of Fig. 4 are adapted to seat on pads 6 that are secured to the truck transom. Otherwise, the function of the links and supports are the same as described above.

It will be evident, from the above description of my invention, that swinging-link bolster connections provide an efficient means for obtaining positive and stable movement of the supported bolster plate relative to the thrust exerted thereon and permit of instantly altering the link supports to provide free swinging motion of the bolster plate relative to the main support from which the links are suspended.

Although I have described a specific embodiment of my invention, it will be obvious to those skilled in the art that various modifications may be made in the details of construction without departing from the principles herein set forth. For instance, the shape of the links and movable supporting blocks may be altered to provide the requisite strength and rigidity for their coacting parts. The specific means for mounting the link mechanism upon a supporting frame is immaterial so long as the type of mounting employed combines freedom of movement of the various parts and, further, it is evident that, although I have specifically described my invention in connection with railway-vehicle steering trucks, it is also applicable to other uses where such movements are desirable.

I claim as my invention:

1. A swing mounting comprising a supporting frame, a plurality of swing links, a swing bolster carried by said links and pivotally connected thereto, a movable and a fixed support for said links, and means for engaging the same with the one or the other of said supports.

2. A swing mounting comprising a supporting frame, a plurality of swing links, a swing bolster carried by said links and piv-

otally connected thereto; a movable and a fixed support for said links; and means for engaging the said links with either of said supports.

3. A swing mounting comprising a supporting frame, a plurality of swing links, a swing bolster carried by said links and pivotally connected thereto, a movable and a fixed support for said links, and actuating means for engaging the same with either of their respective supports.

4. A swing mounting comprising a supporting frame, a plurality of swing links, a swing bolster carried by said links and pivotally connected thereto, a movable and a fixed support for said links, and means for actuating said movable supports into and out of engagement with said links.

5. A swing mounting comprising a supporting frame, a plurality of swing links, a swing bolster carried by said links and pivotally connected thereto, a movable and a fixed support for said links, and means for changing the engagement of said links with said movable and fixed supports.

6. A swing mounting comprising a supporting frame, a plurality of swing links, a swing bolster carried by said links and pivotally connected thereto, a movable and a fixed support for said links, and means for simultaneously changing the engagement of said links with said movable and fixed supports.

7. A swing mounting comprising a supporting frame, a plurality of swing links, a swing bolster carried by said links and pivotally connected thereto, a movable and a fixed support for said links, and means for alternately engaging said movable and fixed supports with said links.

8. A swing mounting comprising a supporting frame, a plurality of swing links, a swing bolster carried by said links and pivotally connected thereto, a movable and a fixed support for said links, and means for simultaneously disengaging said links from one of their supports and effecting engagement with their other supports.

9. A swing mounting comprising a supporting frame, a plurality of swing links, a swing bolster carried by said links and pivotally connected thereto, a movable and a fixed support for said links, and means for simultaneously disengaging said links from their fixed supports and effecting engagement with their movable supports.

10. A swing mounting comprising a supporting frame, a plurality of swing links, a swing bolster carried by said links and pivotally connected thereto, a movable and a fixed support for said links, and means for simultaneously disengaging said links from their movable supports and effecting engagement with their fixed supports.

11. A swing mounting comprising a sup-

porting frame, a plurality of swing links, a swing bolster carried by said links and pivotally connected thereto, a movable and a fixed support for said links, and means for alternately engaging said movable and fixed supports with said links, said means comprising a toggle-joint connection between the movable support and the main frame.

12. A swing mounting comprising a supporting frame, a plurality of swing links, a swing bolster carried by said links and pivotally connected thereto, a movable and a fixed support for said links, and means for alternately engaging said movable and fixed supports with said links, said means comprising a hand-actuated toggle-joint connection between the movable support and the main frame.

13. A swing mounting comprising a supporting frame, a plurality of swing links, a swing bolster carried by said links, and pivotally connected thereto, a movable and a fixed support for said links, and means for

alternately engaging said movable and fixed supports with said links, said means comprising a toggle-joint connection between the movable support and the main frame, and a connecting rod pivotally secured to said toggles to coactively operate the same.

14. A swing mounting comprising a supporting frame, a plurality of swing links, a swing bolster carried by said links and pivotally connected thereto, a movable and a fixed support for said links, and means for alternately engaging said movable and fixed supports with said links, said means comprising a toggle-joint connection between the movable support and the main frame and a connecting rod pivotally secured to the central joint of said toggle to coactively operate the same.

In testimony whereof, I have hereunto subscribed my name this 24th day of October 1922.

FRANK L. ALBEN.
